UNITED STATES PATENT OFFICE.

BERTHOLD MEYER, OF NEW YORK, N. Y.

WINDOW-REFRIGERATOR.

No. 853,589.

Specification of Letters Patent.

Patented May 14, 1907.

Application filed July 5, 1906. Serial No. 324,740.

To all whom it may concern:

Be it known that I, BERTHOLD MEYER, a citizen of the United States, residing in the city, county, and State of New York, have 5 invented a new and useful Improvement in Window-Refrigerators, of which the following is a specification.

My invention relates to improvements in window refrigerators, the objects being to 10 produce a refrigerator in which all the shelves can be inserted and adjusted to accommodate the various articles to be placed in it and to be easily removable for cleaning purposes.

15 Another object is to produce a comparatively deep pocket or series of pockets for holding, say a small quantity of ice in one of the pockets and large bottles or demijohns in another, without in any way interfering 20 with or disarranging the rest of the interior of the refrigerator, or for holding in the separate pockets or compartments different kinds of vegetables.

25 My improved window refrigerator is fully illustrated in the accompanying drawing in which

Figure 1 is a front elevation as viewed from the room the sliding doors being open, and showing the ends of the shelves behind 30 said doors in dotted lines. Fig. 2 is a central sectional view on line o—o of Fig. 1. and Fig. 3 is a sectional plan view of Fig. 1 on line x—x of Fig. 2, showing by dotted lines the widths of the shelves.

35 Similar parts are indicated by like reference numbers.

1 and 2 respectively are the sides of the body, provided with horizontal grooves 3. 4 is the back also provided with grooves 3 on 40 a line with those in the sides.

5 are vertical grooves for the partitions 6 which form the pockets 8, 9, 10. The front 11 of the depending extension is also provided with grooves 5 disposed opposite to 45 those in the back.

12 is the floor of the box resting on the window sill—not shown—and 13 is the floor of the depending extension.

The sides and back are provided with 50 venting holes 14. The roof 15 extends inward a sufficient length to clear the window, and to prevent snow or rain from entering at that point.

The front of the box I prefer to arrange

with two sliding doors 16—17 in such a manner as to offer a view of the interior of the refrigerator when they are pushed open.

18—19 are front walls on either side of proper width: these fronts are also provided with horizontal grooves 3 on line with those 60 in the sides and back.

20 are the adjustable and removable shelves.

Such being the construction of my improved window refrigerator the operation is 65 as follows:—It is understood that the body is made of a proper size to fit the window at which it is to be placed, and secured there in any preferred manner by screws or cleats or otherwise as may be desired. In cold or 70 cool weather no ice will be required, and if the body is made of wood or metal and painted preferably of a white or other very light color, it will shed or throw off the heat of the sun, if it should be so exposed. In the 75 late spring or early fall any proper receptacle containing ice can be placed in one of the pockets 8, 9 or 10. When food is placed on the shelves, if it happens that the dish or article is too high the shelf immediately above 80 can be moved along in the grooves 3 until it clears the front section 18 or 19, when it can be taken out and set aside, thus making what might be called a double space, or if any article too large for one of the pockets is 85 placed in the depending extension, then one of the partitions can be drawn upward and removed from the box or body, thus affording twice the room lengthwise. For cleaning 90 purposes, all the shelves are removed in a like manner, when nothing remains except the walls, roof and bottom of the refrigerator.

The shelves being of a uniform size they 95 will fit into any of the spaces or grooves provided to receive them.

Any number of shelves or any number of partitions for making pockets can be used; I merely show a plurality which may be added to suit the size of the body.

When metal or any other suitable material is used, the same general construction is had, except of course that the conditions of manufacture alters the means of producing grooves or means for supporting the shelves 105 and partitions in which case channels or angles fastened to the body affords a means for accomplishing this purpose.

Having fully described my invention, what I claim as new and desire to secure by Letters Patent is

In a window refrigerator, a box embodying a back, sides, a top, and a front, said front comprising end sections and sliding doors, the said back, the sides and the end sections of the front being provided with registering horizontal grooves, shelves slidably mounted in said grooves, and a depending extension projecting below the bottom of the box at the rear portion thereof, the front

and rear walls of said extension having vertical grooves separating the extension into a plurality of compartments, substantially as described.

In testimony whereof, I have signed my name to this specification in the presence of two subscribing witnesses, this 30th day of June 1906.

BERTHOLD MEYER.
